US00D847153S

(12) United States Design Patent (10) Patent No.: US D847,153 S
Akana et al. (45) Date of Patent: * Apr. 30, 2019

(54) DISPLAY SCREEN OR PORTION THEREOF
WITH GRAPHICAL USER INTERFACE

(71) Applicant: Apple Inc., Cupertino, CA (US)

(72) Inventors: Jody Akana, San Francisco, CA (US);
Imran Chaudhri, San Francisco, CA (US); Christopher Foss, San Francisco, CA (US); Jonathan P. Ive, San Francisco, CA (US); Tiffany Jon, Sunnyvale, CA (US); Chanaka Karunamuni, Cupertino, CA (US); Stephen O. Lemay, San Francisco, CA (US); Marcel van Os, San Francisco, CA (US)

(73) Assignee: Apple Inc., Cupertino, CA (US)

() Term: 15 Years

(21) Appl. No.: 29/613,058

(22) Filed: Aug. 7, 2017

Related U.S. Application Data

(63) Continuation of application No. 29/555,463, filed on Feb. 22, 2016, now Pat. No. Des. 794,045, which is a continuation of application No. 29/466,651, filed on Sep. 10, 2013, now Pat. No. Des. 750,658.

(57) CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing the claimed design; and,

FIG. 2 is another embodiment thereof.

The outermost broken lines in the figures show a display screen or portion thereof, and form no part of the claimed design. The other broken lines in the figures show portions of the graphical user interface that form no part of the claimed design.
